UNITED STATES PATENT OFFICE

2,454,289

PORTABLE SELF-CONTAINED DRUM
CLEANERFrederick E. Neef, Jr., United States Army,
Hartsdale, N. Y.

Application October 16, 1945, Serial No. 622,639

40 Claims. (Cl. 134—81)

(Granted under the act of March 3, 1883, as
amended April 30, 1928; 370 O. G. 757)

1

The invention described herein, if patented may be manufactured and used by or for the Government for governmental purposes, without the payment to me of any royalty thereon.

My invention relates to cleaning machines and more particularly to self-contained automatically operable gasoline engine powered machines for cleaning the interiors of gasoline cans and drums or similar receptacles by flushing the same with a cleaning fluid and simultaneously withdrawing the fluid, filtering it and returning it to the reservoir of the cleaning machine for recirculation, these operations all being automatically controlled.

It is of course well known that cans, drums and receptacles of all kinds for storing or transporting liquids, such as the 5-gallon gasoline cans and 55-gallon drums used by the armed forces, become contaminated during use due to the presence of foreign matter such as tars or resins, sand, dirt, sticks, etc., in the liquid being stored or transported and to the accidental entrance of such foreign materials into the containers through the filling openings therein. Machines have heretofore been designed for the purpose of cleaning such contaminated containers before they are reused, but they all lack the compactness, durability, speed, ease of operation and efficiency desirable. Furthermore, all of these machines are too cumbersome to be readily transported and therefore are not adaptable for use in the field by the armed forces or by others having need for a portable machine. In addition to these deficiencies many of these prior cleaners are unsuitable for use in the field because they do not recirculate the cleaning fluid and therefore require such large quantities of cleaning fluid that the problem of supplying it makes them impracticable. Other cleaning machines use a type of cleaning medium not commonly found in army fuels and lubricants dumps or other army supply sources or readily available thereto so that they are inconvenient to use. It is accordingly an object of my invention to provide a new and improved portable drum cleaning machine which is self contained, compact and durable in construction so that it may be easily transported from place to place without getting out of order, is easy to operate and fast and thorough in operation, but yet is so constructed that it is inexpensive to manufacture.

Another object of the invention is the provision of a new and improved drum cleaner which is entirely automatic in operation and requires only one operator to remove cleaned drums from the machine and load it with contaminated drums.

2

Yet, another object of the invention is the provision of a new and improved cleaner for drums and other containers in which the interiors of the containers are cleaned by being sprayed with a cleaning fluid which after a liquid level has been built up in the containers is withdrawn simultaneously with the spraying during a major portion of the total cleaning cycle so that sand and dirt or other foreign objects are withdrawn with the cleaning fluid while it is still in a turbulent state and before these foreign materials can settle to the bottom of the container.

Still another object of the invention is the provision of a new and improved portable cleaner for drums or other containers which has a cleaning fluid reservoir from which fluid is drawn to spray the interior of the drums for cleaning the same and to which it is returned from the cleaned drums, a filter being provided for removing foreign matter from the fluid before it is returned to the reservoir so that the fluid remains effective for cleaning purposes even after repeated recirculation through the system with the result that the machine may be operated with the expenditure of a minimum amount of cleaning fluid.

Another and further object of the invention is the provision of a new and improved drum cleaning machine in which the vacuum pump is cooled by circulating the cleaning fluid used in operating the machine through the mechanism and back to the cleaning fluid reservoir.

A further object of the invention is the provision of a new and improved cleaning apparatus for drums and other containers in which a fluid such as kerosene, Stoddard solvent or similar types of fluid may be used as a cleaning agent.

A still further object of the invention is the provision of a new and improved portable cleaning machine for drums and other containers which may be readily adapted for cleaning containers of different sizes and shapes.

Another and further object of the invention is the provision of a new and improved portable cleaning machine having a cleaning fluid reservoir adapted to support cleaning nozzles and the containers being cleaned which is itself supported on and rotatable about a fixed vertical axis and which machine includes cams and a valve mechanism cooperating when the reservoir is rotated to subject each container to a plurality of flushing operations during a single revolution of the reservoir.

A further object of the invention is the provision of a new and improved method for cleaning the interiors of drums and other containers which

includes subjecting them to repeated cleaning cycles in each of which there is an initial period of flushing only to build up a fluid level in the containers followed by a period of simultaneous flushing and evacuation of the cleaning fluid so that foreign material dislodged by the discharging cleaning fluid is maintained suspended in the fluid and is withdrawn with the fluid and in discontinuing the flushing and continuing the suction to remove the residual cleaning fluid at the end of the last cleaning cycle.

Another object of the invention is the provision of a new and improved method for cleaning the interiors of drums or like containers in which the containers are subjected to a flushing action by a cleaning fluid which upon withdrawal from the container is filtered to remove the foreign materials and thereafter repeatedly recirculated through the containers, filter and reservoir.

Another and further object of the invention is the provision of a new and improved cleaning apparatus for drums and other containers in which means are provided for supporting the containers being cleaned in an upright position on the machine during the cleaning operation with the cleaning nozzles of the machine projecting into the container through openings in their tops so that the fluid used in flushing the interior of the container is caught in the container and not wasted and after withdrawal and filtering may be recirculated instead of being wasted as in cleaners in which the containers are inverted when they are being cleaned.

A more specific object of the invention is the provision of a new and improved apparatus for cleaning drums and like containers which has a plurality of cleaning nozzles secured on its reservoir that are adapted to be received in the containers being cleaned and suction and pressure means automatically operated upon rotation of the reservoir of the machine to provide simultaneous flushing and evacuation of the containers, the reservoir also being provided with auxiliary connections for cleaning nozzles each having manually operated means for controlling the pressure and suction flow of fluid therethrough so that containers of unusual size and shape not adapted to be secured on the container supports on the machine for automatic cleaning may be cleaned by manually controlling the suction and pressure flow thereto while the container is resting on the base of the machine or other stationary support.

The present invention comprises other novel features, the advantages of which will be pointed out as the description proceeds, the improved cleaner of this invention being fully described hereinafter and the novel features thereof being particularly pointed out in the appended claims. It is to be understood that for the purpose of illustration a preferred embodiment of the cleaning machine has been shown in the drawings and described in detail, but the embodiment shown and described is susceptible of many modifications, changes and rearrangements of parts to fit particular circumstances without departing from the spirit or scope of the invention. In the accompanying drawings:

Figure 1 is a top plan view of my improved cleaning machine.

Figure 2 is a side elevational view of the machine.

Figure 3 is a fragmentary cross sectional view of the base and reservoir of my improved cleaning machine.

Figure 4 is a top plan view of the cleaning machine with the top circular platform and the operating mechanism which it carries removed therefrom.

Figure 5 is fragmentary top plan view of the cleaning fluid reservoir with the operating mechanism removed therefrom.

Figure 6 is a cross-sectional view taken on the line 6—6 of Figure 3.

Figures 7 to 12 inclusive are fragmentary cross-sectional views taken on the lines 7—7 to 12—12, respectively, of Figure 5.

Figure 13 is fragmentary perspective view of a portion of the filter chamber of the cleaning machine.

Figure 14 is a fragmentary front elevational view of the filter chamber of the cleaning machine.

Figure 15 is a side elevational view partly in section of the nozzles used in cleaning five-gallon cans of the type used by the armed forces.

Figures 16 to 22, inclusive, are cross sectional views taken on the lines 16—16 to 22—22, inclusive, respectively, of Figure 15.

Figures 23 is a developed view of the cams for controlling actuation of the suction and pressure valves of the machine.

Figure 24 is a diagrammatic view illustrating the sequence of flushing which a container passes through in a complete cleaning operation.

Figure 25 is a view diagrammatically illustrating the operation of my cleaning machine.

Figures 26 and 27 are top plan views of the suction and pressure cams respectively showing the contour of these cams.

Referring to the drawings there is illustrated therein a cleaning machine particularly adaptable for progressively and automatically cleaning at one time ten five-gallon cans of the type commonly used by the armed forces for storing and transporting gasoline in combat areas and other places. The machine rests on a base 30 formed from a pair of longitudinally extending channel irons 31 which are maintained in spaced relation by a plurality of transversely extending angle irons 32 secured to the channel irons by welding to form a sturdy framework as shown in Figures 1 to 4, inclusive. The space between the cross pieces and channel irons at each end of the base is formed into compartments for storing tools and spare parts by providing a bottom wall of metallic plate for these spaces and covers 33 of the same material which may be hinged to the angle irons or otherwise held in position. Handles 34 are provided on these cover plates for raising the same to gain access to the compartments, and a heavy eyebolt 35 is secured at each corner of the base for lifting the machine when it is to be placed on or removed from its transporting vehicle. Extending transversely of the base is a centrally located channel iron cross piece 36 which has its ends welded to the sides of the longitudinally extending channel irons 31. A supporting column 37 is secured to the central portion of the channel cross piece 36 by welding or other suitable means and is rigidly supported in upright position by a plurality of triangular shaped braces 38 which have vertical edges 39 welded to the sides of the column 37 and body portions that extend diagonally outwardly from the column to the point of intersection between the longitudinal channel irons 31 and the angle iron cross pieces 32, to which the extremities of these body portions are welded as indicated at 40 in Figure 3. This fixed central column forms a

support for the reservoir and the operating mechanism of the cleaner about which it rotates as will be more fully described hereinafter.

A cylindrical reservoir 41 is provided for containing the cleaning fluid used in operating the machine. This reservoir has a sloping bottom 42, vertical walls 43, a central tubular column 44 which extends upwardly from the bottom to a point somewhat below the top edge of the side walls and defines a cylindrical centrally located space into which the central column 37 projects when the reservoir is in operative position. Secured to the inner surfaces of the wall 43 of the reservoir at a point below the top edge and to the outer wall of the tubular column 44 by welding or other suitable means which will provide a liquid and air tight connection between these parts is the reservoir top 45 best seen in Figures 3 and 7 to 11. Spaced above this top 45 and secured along the top edge of the side wall 43 is an annular top plate or flange 46 which forms a base to which the operating valves for controlling the flow of cleaning fluid to and from the containers being cleaned and the posts which support the operating mechanism are secured. The upper end of the tubular column 44 is provided with a flanged ring bearing 47 as shown in Figures 3 and 9, and a thrust bearing 48 is secured on a shoulder 49 near the upper end of the supporting column 37 and is engaged by a flange 50 on the ring bearing 47 to thereby provide a rotatable support for the reservoir as shown in Figure 3. Wobbling of reservoir while it is rotating is prevented by a ring 51 which engages the walls of the tubular column 44 along a slightly enlarged portion 52 thereof when it is resting in position on the collar 53 that is seated on braces 38 of the stationary column 37. This type of mounting permits the reservoir 41 to rotate freely around the stationary column 37.

Two chambers are defined in the top portion of the reservoir through which cleaning fluid must flow in the cycle of a cleaning operation. The first of these is an annular pressure chamber 54 formed around the top of the reservoir by an annular ring 55 which extends between the top of the reservoir 45 and the top plate 46 spaced from the outer wall 43 as shown in Figures 3, 7, 8, 10, and 11. Below this chamber 54 and in the upper end of the reservoir proper a filter chamber 56 is formed between the outer wall 43 of the reservoir, a ring 57 concentric with this wall and secured to the underside of the top 45 of the reservoir by welding and an annular plate 58 welded to the wall of the reservoir and to the edge of the ring to form a bottom for this chamber which slants downwardly toward the right as seen in Figure 3 forming a sump in which foreign materials tend to collect. Periodically it will be necessary to clean out this sump, and for this purpose the reservoir must be provided with an opening normally closed by a clean-out plate (not shown) through which access to the sump may be had.

Set in the outer wall of the reservoir 41 between the bottom 58 of the filter chamber 56 and the bottom 42 of the reservoir is a gauge channel 60 having a vertical wall 61 in which is secured a sight gauge 62 for indicating the level of the cleaning fluid in the reservoir. A second channel 63 is secured along the inner side of the vertical wall of the reservoir and extends from a point adjacent the bottom of the reservoir as shown in Figure 3 to the outlet port 64 formed in the top plate as shown in Figures 5 and 10. 75

This channel forms a passageway for drawing cleaning fluid from the bottom of the reservoir. For draining the reservoir a drain plug 65 is provided which is threaded into a sleeve 66 secured in the wall 43 of the reservoir at a point adjacent its bottom as shown in Figure 12.

Annular ring 57 which forms the inner walls of the filter chamber 56 is provided with two plane portions 67 as shown in Figures 3, 5, 6 and 13, which extend angularly with respect to each other and have internally and externally threaded bushings 68 secured thereto by threading the same therein normal to the surface of the plane portions 67. Elongated tubular filtering screens 69 are threaded into these bushings and extend horizontally from the bushings 68 and angularly with respect to each other so that their outer ends project on opposite sides of the central tubular column 44 of the reservoir as seen in Figure 6. Cleaning fluid is drawn from the containers being cleaned to the filter chamber 56 by means of suction as will be explained in more detail hereinafter and must flow through the strainers 69 in its return passage to the reservoir 41 so that foreign materials are removed. A pressure equalizing screen 70 is provided in the bottom 58 of the filter chamber adjacent the inlet to the screens 69 as seen in Figures 3 and 13.

Supported on the top plate 46 of the reservoir, 30 by means of a plurality of posts 71 secured thereon by threading the same into the plate or by securing them in any other easily removable manner, is a circular platform 72 upon which the operating mechanism for the cleaner is mounted as shown in Figures 1 and 2. This mechanism is of conventional construction and will not be described in detail but includes a pressure pump 73 having an inlet pipe 74 connected to the outlet 64 in the top plate 46 by means of a threaded flange 75 secured to the top plate of the reservoir. An elbow 76 in this conduit 74 is provided with a tapped aperture through which the reservoir is filled with cleaning fluid, and this aperture is closed by a threaded plug 80. In ordinary operation approximately 55 gallons of cleaning fluid are contained in the reservoir which is of almost double this capacity so that it is only about one-half filled with fluid at any time. It has been found that kerosene is an ideal cleaning fluid, not only because of its effectiveness in the cleaning operation but also because of its ready availability at fuel and lubricant supply points for the combat areas when the machine is being used by the armed forces. However Stoddard's solvent or similar cleaning fluids may also be used.

The discharge side of the pump is connected by a conduit 76 seen in Figure 1 to an outlet 77 in the top plate 46 shown in cross section in Figure 11 by means of a threaded flange 78 secured to the top plate to which the end of conduit 76 is threaded. The pump is preferably provided with a by-pass valve to prevent the building up of excessive pressure in the machine.

Flow of cleaning fluid from the machine to the containers being cleaned is produced by the pressure mechanism just described. To produce a return flow of cleaning fluid from the containers to the reservoir, a portion thereof, i. e., the filter chamber 56, and the space in the top of the reservoir above the fluid, are maintained at sub-atmospheric pressure by a vacuum pump 81 secured to the platform 72. A conduit 82 which is connected to the outlet 83 in the top plate 46 through a threaded flange 84 secured to the top plate and threadedly receiving the end of conduit

7
62 as shown in Figure 8 connects the pump 81 with a channel 85 which extends from the top plate downwardly through the pressure chamber 54 into the filter chamber 86 and is welded to the underside of the top plate and to the walls 46 of the reservoir to form an air tight passage-way from the filter chamber to the outlet 83.

In the operation of the machine, air is drawn from the filter chamber and the upper part of the reservoir by the vacuum pump 81 and is exhausted to the atmosphere through a conventional air exhaust and silencer 88 shown in Figure 2. The cleaning nozzle communicate with this region of reduced pressure through means to be herein-after described so that suction on the nozzles causes a return flow of cleaning fluid.

Forced lubrication of the vacuum pump 81 is obtained by means of an oil pump 86 mounted above the platform 72 and having conduits 81 for feeding oil to the vacuum pump, and to prevent overheating of the vacuum pump in the operation of the cleaning machine it was found necessary to provide a means for cooling the same. In the present embodiment of the invention this is accomplished by bypassing a small portion of the cleaning fluid from the pressure pump 73 through a by-pass conduit 89 to the vacuum pump and circulating the same therethrough. Thus the compactness of the machine is increased since the need for a separate cooling medium for the pump is eliminated. Moreover, a further saving in space and equipment is secured by this cooling system because it is not necessary to provide a heat exchanger for cooling the cleaning fluid. Aeration of the fluid is bound to occur when the cleaning fluid is sprayed into the containers being cleaned so that the fluid is maintained in a relatively cool condition at all times.

The means for driving these pumps 73, 81 and 86 preferably comprises an air cooled internal combustion engine 90 of conventional construction secured to platform 72, although other operating means may be used if more convenient. Referring to Figures 1 and 2 it will be seen that this engine drives a gear reducer 91 which in turn drives a hub 92 through a clutch having an operating handle 93 for operatively engaging and disengaging the engine and the hub. A sprocket 94 secured on the outer end of the hub 92 drives the oil pump through a sprocket chain which engages over a sprocket on the drive shaft of the oil pump.

A second sprocket 95 on the hub 92 is connected to and drives the vacuum pump 81 when the hub is rotating. The pressure pump is also driven from this hub 92 by means of a third sprocket 96 connected by a sprocket chain to a sprocket on the pressure pump 73. The fourth sprocket 97 on the hub is connected by a chain to a speed reducer 98 secured on the platform and having a vertically extending shaft 99 projecting below the platform 72 and rotated at a reduced speed with respect to the hub 92 and motor shaft when the motor and hub are operatively engaged.

Engine 90 has a crank 100 which extends outwardly beyond the platform 72 to an accessible position so that it may be conveniently operated manually when it is desired to start the engine. By means of the clutch between the engine and the hub it is possible to disconnect the engine from the pumps secured on the platform when the engine is to be started or cleaning is to be discontinued. It should be noted that by securing the operating mechanism to the platform as described this mechanism may be easily and quickly removed from the machine as a unit merely by

disconnecting the posts 71 and the suction and pressure connections to the reservoir. The whole platform 72 and everything secured on it may then be lifted from the machine.

In addition to driving the pumps beforementioned, the engine 90 also rotates the reservoir upon the fixed column 37 during the cleaning operation. In Figures 2 and 3, there is shown a means for driving the reservoir from the motor which comprises a clutch having fixed and movable elements. The fixed element of the clutch comprises a circular plate 101 having a ring 102 engaging about the top of the fixed column 37 and non-rotatably secured thereto by means of set screws 102' or other suitable means. This plate is provided with rectangular slots in its periphery in which the lower ends 103 of a series of elongated jaw teeth 104 secured in the periphery of a movable disc 105 are adapted to slide when the disc 105 is raised or lowered. The upper ends of the jaw teeth 104 extend upwardly above the top surface of the disc 105.

The second element of the clutch comprises a jaw element 106 having peripheral slots 107 in which the upper ends of the teeth 104 are adapted to engage when the disc 105 is raised to operative position.

Jaw element 106 is secured to the lower side of an idler sprocket 108 which is free to rotate upon a shaft 109 depending from the lower side of the platform 72 and coaxial with the column 37. Idler 108 is driven through a sprocket chain 110 by a sprocket 111 secured on the shaft 99 depending from and driven by the speed reducer 98. When the teeth 104 in the disc 105 are disengaged from the clutch element 106 on the idler 108 as shown in Figures 2 and 3, the latter is free to rotate upon its shaft and the reservoir remains stationary even though the engine is operating. However, when the movable disc 105 is raised from the position shown in the drawings sufficiently to cause the tops of the teeth 104 to engage in the slots 107 in the periphery of the idler element 106, their lower ends will remain engaged in the slots in the periphery of the circular plate 101 fixed to the stationary column 37 so that rotation of the idler will be abruptly braked and the sprocket chain will stop moving over the sprockets, but with the engine 90 continuing to operate and to apply torque to the sprocket 111 the force applied will cause this sprocket to travel along the sprocket chain 110 so that the entire platform 72 and all of the mechanism secured thereto will be rotated about a vertical axis coaxial with the axis of the idler 108 and stationary column 37. Since the platform 72 and reservoir 41 are rigidly and non-rotatably secured together by means of the posts 71 secured to the platform 72 and to the top plate 46 of the reservoir the latter will be caused to rotate about the fixed column 37 on the thrust bearing 48 which supports the machine on column 37. Under normal operating conditions the reservoir travels relatively slowly making one revolution in approximately 70 seconds so that the sudden engagement of the clutch elements does not place too great a strain thereon.

Means for raising and lowering the circular disc 105 is shown in Figure 3 comprising a shaft 112 threaded at its upper end into the disc 105 which is locked on this shaft by a nut 113 threaded on the upper end thereof. The shaft is journaled adjacent its upper and lower ends for reciprocatory movement in a centrally located opening in the fixed plate 101 and an opening 114 in the top of the central cross bar 36 and is piv-

oted at its lower end to one arm of a bell crank lever 118 pivoted at 116 to a cross piece 117 extending between the flanges of the central cross bar 36. The other arm of the bell crank is pivoted to one end of an operating rod 118 extending longitudinally of the base 30 and provided with an upturned handle 119 on its outer end for convenient grasping by an operator. It will be obvious from an examination of Figures 2 and 3 that by moving the rod 118 to the right as shown in those figures the shaft 112 and disc 105 will be raised until the teeth 104 engage in the slots 107 in the idler clutch element 106. The clutch may be locked in engaged position by providing the rod 118 with a slot 120 on its underside positioned so that it engages with the edge of an upstanding bracket 121 secured to the base 30 when the disc is in fully raised position.

To prevent the reservoir from rotating when the machine is idle or is being transported, it may be provided with a plurality of anchors similar to that shown at 122 in Figure 2. Each anchor comprises a pair of tie rods 123 having their adjacent ends threaded into a turnbuckle 124 and their outer ends adapted to be engaged in the plate 46 of the reservoir and an eye adjacent the outer extremity of a side rail 31 of the base 30. By tightening the turnbuckles 124 the reservoir may be rigidly locked against accidental rotation.

In the operation of the machine, cleaning of the containers and removal of the foreign materials therefrom is effected by simultaneously flushing and evacuating the containers for a portion of each cleaning cycle so that cleaning fluid is withdrawn while it is still in a turbulent state due to the flushing or so soon thereafter that the foreign materials have not had time to stick to the sides of the container or settle to the bottom.

A compact nozzle for accomplishing simultaneous flushing and evacuation of the containers is shown in Figure 15 from which it will be readily apparent that each nozzle consists of concentric inner and outer metallic tubes 125 and 126, respectively, which are sealed together at their lower ends as indicated at 127 so that a cylindrical inner passageway 128 and an annular outer passageway 129 are defined in each nozzle. The upper end of the outer tube 126 is secured to one branch of a T joint 130 by a leakproof connection, and the inner tube 125 extends through both branches of the T connection 130 and communicates with a connecting pipe 131, one end of which is threaded into the second branch of the T. Both the joint between the T 130 and the end of connecting pipe 131 and between the upper end of the inner tube 125 and the interior of the connecting pipe 131 are made leakproof so that there is no communication between the inner and outer passageway 128 and 129 in the nozzle.

The outer tube 126 of the nozzle is provided with small jet apertures 132 arranged in series indicated generally in Figure 15 and at various angles to the surface of the tube to direct fluid in the form of a fine stream or spray from the nozzle onto all the interior surfaces of the container which has been placed about the nozzle as shown in Figure 2. The series of apertures 132 shown in Figure 15 and the particular arrangement thereof which is indicated in Figures 16 to 22 was designed particularly for cleaning five-gallon cans of the type used by the armed forces in storing and transporting gasoline in combat areas. It will be obvious that other arrangements of apertures may be made to make the nozzles

adaptable for cleaning containers of other sizes and shapes.

Each nozzle is rigidly supported in depending position by upwardly projecting supply and evacuation conduits which are connected thereto at one end and at the other end communicate with the proper chambers of the reservoir to effect the flushing operation. The stem of the T 130 is connected to the upper end of a fluid supply conduit 133 which conduit is connected at its lower end to an automatically operated pressure valve 134. Interposed in this line at any convenient point beyond the pressure valve 134 for example between the stem of the T 130 and the upper end of the conduit 133 is a manually operated valve 135 for regulating the flow of fluid to the nozzle independently of the operation of the pressure valve 134 and for completely discontinuing the operation in certain nozzles when this is desired. Pressure valve 134 is in the form of a conventional poppet or whistle valve and in turn is connected to the top plate 46 by a short length of pipe 136 threaded into one of the series of threaded openings 137 therein (shown in Figure 5) which communicate with the pressure chamber 54. By means of the pressure line just described the outer passageway 129 in a nozzle is brought into communication with the pressure chamber 54 so that fluid under pressure will flow into the nozzle when the valve 134 is opened.

Valve 134 is spring loaded in a closing direction so that a force must be applied to its stem 138 when the valve is to be opened. For accomplishing this automatically an operating mechanism 35 is provided comprising a horizontally extending lever arm 139 having one end engaging the valve stem and having its opposite end rigidly secured on the upper end of a vertical spindle shaft 140 which is rotatably mounted in a flanged journal 141 secured to the top plate 46 of the reservoir as shown in Figures 3 and 4 and extends through one of the series of openings 142 in the top plate 46 shown in Figure 5. Rigidly secured on the lower end of the spindle 140 is a second lever arm 143 which also extends horizontally therefrom. The outer end of this arm is provided with a roller 144 for engaging the cam surface of a cam which will be described hereinafter, and the two lever arms are secured on center lines angularly disposed with respect to each other sufficiently to cause the valve stem and first lever arm to remain in contacting engagement and the roller and cam surface to remain in contacting engagement at all times.

Support for the nozzle is also provided by the suction conduit 145 connected at its upper end to the upper end of the connecting pipe 131 on the nozzle through elbow fittings a coupling and short connecting pipes. A manually operable valve 146 similar to the valve 135 in the pressure line is interposed in the line preferably between the coupling and the suction line as shown in Figure 2. The lower end of the suction conduit is connected by means of a series of connecting pipes and elbows to the outlet side of a gate valve 147 which has its inlet connected through an air-tight connecting gasket 148 to the top plate 46 of a reservoir as indicated in Figure 3 so that the inlet of the valve communicates with a passageway 149 leading to the filter chamber 56 as seen in section in Figure 7.

The gate in valve 147 is mounted on a vertically extending spindle 150 which rotates to swing the gate into an out of seated position. Spindle 150

extends through and is rotatably journaled in one of a series of apertures 161 in the top plate 46 and has a horizontally extending lever arm 162 rigidly secured on its lower end. Referring to Figure 3 it will be seen that this arm has a roller 153 on its free end engageable in a cam race in a suction cam which will be described hereinafter for operating the lever.

For the sake of brevity a single nozzle and its suction and pressure supply system have been described because each of the ten nozzles and the supply lines therefor are similar in construction and operation. Mutual support as between the vertically extending portion of the suction and pressure supply lines is obtained by means of a strap metal band 154 encircling the ten series of conduits 133 and 145. Each conduit is secured to the band by means of a U-bolt 155 so that all the conduits are bound together and mutually support each other and thus increase the rigidity of the entire structure.

In order that the cleaning operation may be satisfactorily performed, a container being cleaned must be supported on the machine in an upright position, but tilted sufficiently so that the lower corner of the container diagonally opposite the opening therein is the lowest point of the container, and the nozzle tip must project into this lowest point. One form of support for accomplishing this shown in Figures 2 and 4 comprises an elongated supporting arm 156 pivotally secured at one end to the upper end of a holder bracket 157. This holder 157 pivots upon a vertically extending pin 158 secured in upper and lower lugs 159 and 160 respectively welded to the side walls 43 of the reservoir as seen in Figure 7. Extending angularly downwardly from a projection 161 on the lower side of the arm 156 intermediate its ends is a compression spring 162 which seats against the edge of the bracket 157. The upper edge of the arm is declined to a point intermediate its ends where a projection 163 is provided to form an abutment for the edge of a container when the latter is in position for cleaning. A handle 164 for gripping the arm is fastened on the outer extremity thereof, and the bracket may be provided with stop plates 165 on each side adapted to engage the side walls 43 of the reservoir for limiting pivotal movement of the holder on the pin 158.

In placing a can on the machine preparatory to cleaning the same the arm 156 is pivoted to one side or the other and a container manually raised to position with a nozzle projecting into its interior through the opening on the top side of the container. The operator then grasps the handle 164 and pivots the arm of the can holder downwardly against the pressure of the spring 162 and horizontally until it is brought under the edge of the can with the back edge of the latter abutting against the projection 163. For aiding in properly positioning the can a guide 166 may be secured to the lower end of the suction conduit 145 by a U-bolt 167. To prevent escape of cleaning fluid from the opening of the container during the cleaning operation each nozzle preferably is provided with a cap or apron 168 secured on the nozzle at such a position that the top of the can is brought into engagement with the edges of the apron when the can is in proper cleaning position. In addition to its other functions the apron also aids in properly positioning a container on the machine.

While only one can support 156 has been de-

scribed, it should be obvious that a similar support is provided in conjunction with each nozzle on the machine.

Automatic operation of the pressure and suction flow is secured by means of pressure and suction cams now to be described, having reference particularly to Figures 3, 4, 26, and 27 in which the same are illustrated. The suction cam designated in its entirety by the number 169 comprises a plate 170 having the contour shown in Figure 26, a ring 171 secured to this plate along its periphery and a plurality of generally sector shaped plates 172 secured to the ring 171 in spaced relation with the plate 170 to form a series of cam races 173 with the plate in which the rollers 153 on the end of the suction cam levers 162 are adapted to move. Plate 170 is non-rotatably secured by means of welding or other appropriate means to a hub 174 adapted to be received on the upper reduced end of the fixed column 37. Reinforcement of the union between these parts is obtained by means of a plurality of triangular shaped braces 175 having vertical edges welded on the periphery of the hub at their junction and longitudinal edges welded to the top of the plate 170.

A pressure cam 176 in the form of a ring and having the contour shown in Figure 27 is secured to the uppermost side of the suction cam by means of rivets or bolts or other suitable means and is held in spaced relation therewith by spacers 177 interposed between the two cams.

Since the valves and their operating levers are mounted on the top plate 46 of the reservoir and 35 rotate therewith, the cams must remain stationary if the valves are to be operated when the reservoir is rotated. Fixed mounting of the cams is secured by means of a plurality of set screws 174' which are threaded into the walls of the hub 40 174 and bear against the fixed column 37 when the cams are in position on the column.

As indicated in Figures 3 and 4 the rollers 144 on the pressure cam levers 143 ride on the outer surface of the pressure cam 176 and as previously explained are held in contact therewith by the spring loaded stems of poppet valves 134. The springs in these valves tend to hold them in closed position so that a positive pressure is required to open the valve. This along with the 50 particular contour of the pressure cam 176 and the relative angular positioning of the cam lever arms 139 and 143 on the spindle 140 causes the pressure valve 134 to be opened and closed instantaneously for abruptly initiating or terminating the flow of fluid to the nozzles. On the other hand, the gate valves 147 in the suction line must be mechanically operated in both opening and closing directions. For this reason the suction 55 cam is provided with cam races 173 in which the cam rollers 153 move so that the cam levers are forceably operated in both opening and closing directions.

Referring to Figures 4 and 23, and to Figure 24 65 wherein is shown the sequence of operation of the valves, it will be noted that throughout each cleaning cycle operation of the suction valve is delayed with respect to operation of the corresponding pressure valve. This is indicated in Figure 23 which is a diagrammatic developed view of the cams with the oblique lines joining positions representing the valves. It will be noted that the pressure valves open abruptly and in advance of the suction valves which open slowly 70 and that no more than three suction and three 75

pressure valves are open at any one time. By limiting the operation in this manner the capacity of the machine is not overtaxed and the cleaning cycle can be repeated during each complete cleaning operation to secure more effective cleanings.

In Figure 24 is shown the sequence of the cleaning operation with the operator's station indicated. It should be noted that a complete cleaning operation has three cycles, and that during the first and second cycle of the cleaning operation there is a relatively long period of flushing initiated sufficiently in advance of the opening of the suction valve so that a liquid level is built up in the container being cleaned and is maintained throughout these two cycles. Foreign materials dislodged from the walls of the container are suspended in this liquid and are prevented from settling too rapidly by the turbulence of the liquid caused by the discharging fluid. As this turbulent liquid is drawn from the container the foreign materials suspended therein are also withdrawn. Flushing during the third cycle is continued only a sufficient time to stir up the liquid carried over from the second cleaning cycle and the suction in this cycle is continued a sufficient time to completely evacuate the container and thereafter is continued at a reduced rate to a point in the path of rotation where the containers are removed by the operator in order to prevent a back flow of cleaning fluid from the nozzle into the container being cleaned.

In addition to the nozzles already described the machine is also provided with one or more auxiliary nozzles 178 particularly adapted for cleaning containers other than the five-gallon container, for example 55-gallon drums. These nozzles are similar in construction to the nozzle previously described and are provided with manually operated valves 179 for controlling the flow of fluids therethrough. Nozzles 178 are connected by flexible hoses 180 shown in Figure 1 to pressure and suction outlets on the reservoir indicated generally at 181 and provided with manually controlled valves 182.

When these nozzles are to be used they are connected to the proper outlets 181 to produce a circulation of fluid therethrough and the pressure and the suction creating mechanism of the machine is put in operation, but the driving clutch 105 for the reservoir is allowed to remain disengaged so that the reservoir remains stationary. When the valves 179 controlling the flow of fluid are open with the nozzles 178 inserted in a drum, a circulation of fluid will occur. This may be continued for a sufficient length of time to effect a thorough cleaning of the drum which during this time is placed adjacent but not on the machine. The manually operated valves 179 should be opened and closed in such order that a sequence of pressure and suction flow is secured similar to that secured in the automatic operation of the machine.

For the automatic operation of the machine the reservoir is first supplied with cleaning fluid, preferably kerosene, which is fed into the reservoir through the filling opening in elbow 78. After the machine has been loaded with ten cans and the operating engine 90 has been started, the clutch for driving the operating mechanism is engaged by moving the lever 93 thereby causing kerosene to be drawn from the bottom of the reservoir 41 through the channel 63 outlet 64 and conduit 74 to the intake side of the pump 73. Kerosene under pressure is forced from the pump

through conduit 76 and inlet 77 into the annular pressure chamber 54 in the top of the reservoir 41.

At the same time that pressure is being built up in the pressure chamber, the pressure in the filter chamber and reservoir is being reduced to sub-atmospheric by the vacuum pump 81 which is connected to the filter chamber 56 through the conduit 82 outlet 83 and passageway 85. Adjustment of the capacity of these pumps must be made to prevent a back flow of air through the pressure line since both pumps are evacuating fluid from the same chamber. I have found that a pressure pump capable of creating a vacuum of about 25 inches of mercury and a vacuum pump having a capacity of about 15 inches of mercury will produce satisfactory degrees of pressure and vacuum for operating the machine without overtaxing either pump.

By maintaining the filter chamber 56 and reservoir 41 at sub-atmospheric pressure at all times, a flow of contaminated fluid from the containers being cleaned to the filter chamber will occur whenever any of the suction valves 147 are open.

The path of flow of contaminated fluid from the lower corner of the container is through inner passageway 128 in the nozzle, connecting pipes, coupling and manually operated valve 146 into suction conduit 145 and to suction valves 147 from which it flows into filter chamber 56 through the passageway 149 shown in Figure 7. From the filter chamber 56 the fluid is returned to the reservoir through the strainers 69 whereby foreign materials are removed.

After the operating mechanism has functioned for a sufficient time to create the proper pressure differential between the pressure and filter chambers to produce a circulation of cleaning fluid, the disc 105 is engaged with element 106 whereupon the platform 72 and the reservoir 41 are rotated. During this rotation the cam rollers 144 and 153 are carried over the camways on the pressure and suction cams, and as a result, operate the flow control valves 134 and 147 in the sequence previously described. One operator is stationed at the point 183 shown in Figure 24 to remove the cleaned cans from the machine and place contaminated cans on the machine. In all other respects, the operation of the machine is automatic. By operating the machine in this manner and with the reservoir making a complete revolution in approximately seventy seconds, it has been found possible to clean upwards of 3,000 cans in a single eight-hour day.

Obviously, many modifications in the size, structure and arrangement of parts described above are possible in the construction of a machine for carrying out the invention. Therefore, I do not desire to be limited to the precise details described above, but desire to avail myself of all the novel aspects of the invention coming within the scope of the appended claims.

I claim:

1. A self-contained apparatus for cleaning the interiors of containers comprising in combination, a rotatable cleaning fluid reservoir, means for supporting a plurality of containers on said reservoir in position for cleaning, a plurality of cleaning nozzles adapted to be received in said containers for flushing said containers with cleaning fluid and evacuating the same therefrom, means connected with said nozzles and said reservoir for subjecting a portion of said cleaning fluid to pressure, means for applying suction to said nozzles for evacuating cleaning

15

fluid from said containers to said reservoir, motor means for rotating said reservoir and for operating said suction and pressure means, and control means operable upon rotation of said reservoir for controlling the pressure and suction flow between said reservoir and said nozzles to delay the application of suction to said nozzles at the beginning of the cleaning cycle until a fluid level has been built up in said container and to continue suction at the end of a cleaning cycle a sufficient time to insure complete evacuation of the residual fluid from said containers. 5 10

2. A self-contained apparatus for cleaning the interiors of containers comprising in combination, a rotatable cleaning fluid reservoir, means for supporting a plurality of containers on said reservoir in position for cleaning, a plurality of cleaning nozzles adapted to be received in said containers for flushing said containers with cleaning fluid and evacuating the same therefrom, means connected with said nozzles and said reservoir for subjecting a portion of said cleaning fluid to pressure, means for applying suction to said nozzles for evacuating cleaning fluid from said containers to said reservoir, motor means for rotating said reservoir and for operating said suction and pressure means, and control means operable upon rotation of said reservoir for controlling the pressure and suction flow between said reservoir and said nozzles to effect simultaneous flushing and evacuation of said containers after a liquid level has been built up therein followed by evacuation only for removing the residual cleaning fluid from said containers after said pressure flow has been discontinued by said control means.

3. A self-contained apparatus for cleaning the interior of containers comprising in combination a rotatable cleaning fluid reservoir, means for supporting a plurality of containers on said reservoir, a series of cleaning nozzles on said reservoir each adapted to be received in one of said containers and having a discharge passageway with outlets therein for directing a cleaning fluid on all of the interior surfaces of said container and an evacuation passageway for withdrawing cleaning fluid from said container, means for establishing a flow of cleaning fluid under pressure from said reservoir to the said discharge nozzles, means for simultaneously creating a suction flow from said nozzles to said reservoir, valve means for controlling the flow of fluid to and from said nozzles, stationary cam means, and actuating means for opening and closing said valve means, said actuating means rotating with said reservoir and engaging with said cam means, said cam means being conformed to operate said actuating means for opening and closing said valves in predetermined order during a cleaning cycle to provide an initial period of discharge only from said nozzles followed by a period of simultaneous discharge and evacuation and a terminating period of evacuation only when said reservoir is rotated.

4. A cleaning apparatus as set forth in claim 3 wherein the cam means are designed and adapted to operate said actuating means for said valves through a plurality of cleaning cycles during each complete revolution of said reservoir.

5. A self-contained apparatus for cleaning the interior of containers comprising in combination a cleaning fluid reservoir, means for supporting a plurality of containers in position for cleaning, a plurality of cleaning nozzles communicating with said reservoir and adapted to be received

in said containers, a pressure chamber, a pressure pump for transferring cleaning fluid under pressure from said reservoir to said pressure chamber, means connecting said pressure chamber and said nozzles for conveying fluid under pressure to said nozzles for flushing said containers, means for applying a suction to said nozzles for evacuating the cleaning fluid from said containers and returning same to said reservoir, means for controlling the flow of fluid to and from said containers, means for rotating said reservoir, cam means for engaging with said flow control means to actuate the latter upon rotation of the reservoir through repeated cleaning cycles during each revolution of the reservoir, said cam means being conformed to operate said flow control means in sequence to provide an initial period of flushing only followed by a period of simultaneous flushing and evacuation and a terminating period of evacuation only.

20 minating period of evacuation only.

6. A self-contained apparatus for cleaning the interior of containers comprising in combination a cleaning fluid reservoir, means for supporting a plurality of containers in position for cleaning, 25 a plurality of cleaning nozzles communicating with said reservoir and adapted to be received in said containers, pressure means communicating with said nozzles and said reservoir for conveying cleaning fluid under pressure to said nozzles for flushing said containers, means for reducing the pressure to sub-atmospheric in the portion of said reservoir above the level of the fluid therein, a filter chamber in communication with said reservoir, means connecting said filter 30 chamber and said nozzles for conveying contaminated cleaning fluid from said containers to said filter chamber, means for controlling the flow of fluid to and from said containers, means for rotating said reservoir, cam means for engaging 35 with said flow control means to actuate the latter upon rotation of the reservoir through repeated cleaning cycles during each revolution of the reservoir, said cam means being conformed to operate said flow control means in sequence 40 to provide an initial period of flushing only followed by a period of simultaneous flushing and evacuation and a terminating period of evacuation 45 only.

7. A self-contained apparatus for cleaning the interior of containers comprising in combination a cleaning fluid reservoir, means for supporting a plurality of containers in position for cleaning, a plurality of cleaning nozzles adapted to be received in said containers, a pressure chamber, a pressure pump for transferring cleaning fluid under pressure from said reservoir to said pressure chamber, means connecting said pressure chamber and said nozzles for conveying fluid under pressure to said nozzles for flushing said containers, a vacuum pump having its suction side connected to said reservoir above the level of the fluid therein for reducing the pressure in said chamber to sub-atmospheric, a filter chamber in communication with said reservoir, means connecting said filter chamber and said nozzles for conveying contaminated cleaning fluid from said containers to said filter chamber, means for controlling the flow of fluid from said pressure chamber to said nozzles and from said nozzles to said filter chamber, means for rotating said reservoir, cam means for engaging with said flow control means to actuate the latter upon rotation of the reservoir through repeated cleaning cycles during each revolution of the reservoir, said cam means being conformed to operate said flow con-

trol means in sequence to provide an initial period of flushing only followed by a period of simultaneous flushing and evacuation and a terminating period of evacuation only.

8. A self-contained apparatus for cleaning the interior of containers comprising in combination a cleaning fluid reservoir, means for supporting a plurality of containers in position for cleaning, a plurality of cleaning nozzles adapted to be received in said containers, a pressure chamber, a pressure pump for transferring cleaning fluid under pressure from said reservoir to said pressure chamber, means connecting said pressure chamber and said nozzles for conveying fluid under pressure to said nozzles for flushing said containers, a vacuum pump having its suction side connected to said reservoir above the level of the fluid therein for reducing the pressure therein to sub-atmospheric, a filter chamber in communication with said reservoir, means connecting said filter chamber and said nozzles for conveying contaminated cleaning fluid from said containers to said filter chamber, poppet valves in said pressure flow means and throttle valves in said vacuum flow means for controlling the flow of fluid therethrough, lever arms on said valves for operating the same, means for rotating said reservoir, cam means for engaging said lever arms to actuate said valves upon rotation of the reservoir through repeated cleaning cycles during each revolution of the reservoir, said cam means being conformed to operate said flow control means in sequence to provide an initial period of flushing only followed by a period of simultaneous flushing and evacuation and a terminating period of evacuation only.

9. A self-contained apparatus for cleaning the interior of containers comprising in combination a cleaning fluid reservoir, means for supporting a plurality of containers in position for cleaning, a plurality of cleaning nozzles communicating with said reservoir and adapted to be received in said containers, pressure and suction means communicating with said nozzles and said reservoir to circulate cleaning fluid to and from said nozzles for flushing the interior of said containers and removing the foreign material therefrom with said cleaning fluid, means for controlling the flow of cleaning fluid in said pressure and suction means, a fixed shaft forming an axis for said reservoir, means for securing said reservoir on said shaft in rotatable relation therewith, means for driving said cleaning apparatus, clutch means for disengageably connecting said reservoir and said driving means, stationary cam means engaging with said flow control means to actuate the latter upon rotation of said reservoir through repeated cleaning cycles during each revolution of said reservoir, said cam means being conformed to operate said flow control means in a sequence providing an initial period of flushing only followed by a period of simultaneous flushing and evacuation and a terminating period of evacuation only.

10. A self-contained apparatus for cleaning the interior of containers comprising in combination a cleaning fluid reservoir, means for supporting a plurality of containers in position for cleaning, a plurality of cleaning nozzles communicating with said reservoir and adapted to be received in said containers, pressure and suction means communicating with said nozzles and said reservoir to circulate cleaning fluid to and from said nozzles for flushing the interior of said containers and removing therefrom foreign material with

said cleaning fluid, means for controlling the flow of cleaning fluid in said pressure and suction means, a fixed vertical shaft forming an axis for said reservoir, thrust bearing means for supporting said reservoir upon said shaft in rotatable relation therewith, means for driving said cleaning apparatus, clutch means for disengageably connecting said reservoir and said driving means, stationary cam means upon said shaft for engaging with said flow control means to actuate the latter upon rotation of said reservoir through repeated cleaning cycles during each revolution of said reservoir, said cam means being conformed to operate said flow control means in a sequence providing an initial period of flushing only followed by a period of simultaneous flushing and evacuation and a terminating period of evacuation only.

11. A self-contained apparatus for cleaning the interior of containers comprising in combination a cleaning fluid reservoir, means for supporting a plurality of containers in position for cleaning, a plurality of cleaning nozzles communicating with said reservoir and adapted to be received in said containers, pressure and suction means communicating with said nozzles and said reservoir to circulate cleaning fluid to and from said nozzles for flushing the interior of said containers and removing the foreign material therefrom with said cleaning fluid, valves in said pressure and suction means for controlling the flow of cleaning fluid therethrough, lever arms for opening and closing said valves, a fixed shaft forming an axis for said reservoir, means for securing said reservoir on said shaft in rotatable relation therewith, means for driving said cleaning apparatus, clutch means for disengageably connecting said reservoir and said driving means, a cam fixed on said shaft for engaging with the lever arms on said pressure valves and a second cam on said shaft for engaging with the lever arms on said suction valves for operating said valves upon rotation of said reservoir to flush said containers with cleaning fluid and evacuate the same therefrom, said second cam being arranged to delay operation of said suction valves with respect to the corresponding pressure valves in each cleaning cycle.

12. A cleaning apparatus of the type defined in claim 11 wherein said cams are conformed to operate each of said valves through a plurality of complete cleaning cycles during each revolution of said reservoir.

13. A self-contained apparatus for cleaning the interior of containers comprising in combination a rotatable cleaning fluid reservoir, a plurality of cleaning nozzles secured on said reservoir and rotatable therewith, means for supporting a plurality of containers on said reservoir with said cleaning nozzles projecting into said containers, means for supplying cleaning fluid under pressure to said nozzles for flushing said containers, suction creating means for evacuating said containers through said nozzles, valve means for controlling the flow of cleaning fluid in said supply and evacuation means, actuating means for opening and closing said valve means when said reservoir is rotated, means for driving said cleaning apparatus, a stationary post for supporting said reservoir, a clutch element co-axially fixed on said post, an idling clutch element operatively connected to said driving means, means for engaging said idling element and said fixed clutch element for locking said idling element in fixed position and thereby causing said driving means to be

19

rotated about an axis co-axial with said post, means for supporting said driving means on said reservoir to cause the latter to be rotated when said driving means is rotated, and cam means non-rotatably secured on said post, said operating means for said valves engaging said cam means and being operated thereby to open and close said valves in predetermined order when said reservoir is rotated for simultaneously flushing and evacuating the interior of said containers to clean the same.

14. A self-contained apparatus for cleaning the interior of containers comprising in combination a cylindrical cleaning fluid reservoir, means for supporting a plurality of containers on said reservoir, a series of nozzles on said reservoir adapted to be received in said containers and having discharge passageways with outlets therein for directing a cleaning fluid on all of the interior surfaces of said containers and an evacuation passageway for withdrawing fluid from said containers, a platform supported on said reservoir, a pressure pump on said platform for establishing a forced flow of cleaning fluid from said reservoir to said nozzles, a vacuum pump on said platform for creating a suction flow of cleaning fluid from said nozzles to said reservoir, a motor on said platform for driving said pumps and for rotating said reservoir, a stationary post for supporting said reservoir and platform, a clutch element coaxially fixed on said post, an idling clutch element operatively connected to said motor, means for engaging said idling element and said fixed element for locking said idling element in fixed position and thereby causing said platform and reservoir to be rotated about said post when said motor is operating, valve means for controlling the flow of cleaning fluid to and from said nozzles, cam means secured on said post, cam levers operatively connected to said valves and operated by said cams for opening and closing said valves in predetermined order upon rotation of said reservoir to provide a period of flushing only of said containers followed by a period of simultaneous flushing and evacuation for cleaning the interior of said containers and terminated by a period of evacuation only for removing residual cleaning fluid from said containers.

15. A self-contained apparatus for cleaning the interior of containers comprising in combination a cleaning nozzle adapted to be received in a container and having a discharge passageway therein with outlets for directing cleaning fluid on the interior surfaces of said container and an evacuation passageway for withdrawing fluid from said container, a cleaning fluid reservoir, means for establishing and maintaining a flow of fluid under pressure from said reservoir to the discharge passageway in said nozzle for flushing the interior of said container, means for creating a suction flow from said nozzle to said reservoir for evacuating said container, and means for controlling the flow of fluid to and from said nozzle to delay the initiation and termination of the suction flow with respect to the pressure flow.

16. A self-contained apparatus for cleaning the interior of containers comprising in combination a cleaning nozzle adapted to be received in a container and having a discharge passageway therein with outlets for directing cleaning fluid on the interior surfaces of said container and an evacuation passageway for withdrawing fluid from said container, a cleaning fluid reservoir, means for establishing a flow of fluid under pressure from said reservoir to the discharge passageway in said

nozzle for flushing the interior of said container, means for simultaneously creating a suction flow from said nozzle to said reservoir for evacuating said container, means for controlling the flow of fluid to and from said nozzle to maintain a substantially constant level of turbulent fluid in said containers while they are being cleaned.

17. A self-contained apparatus for cleaning the interior of containers comprising in combination a cleaning nozzle adapted to be received in a container and having a discharge passageway therein with outlets for directing cleaning fluid on the interior surfaces of said container, and an evacuation passageway therein for withdrawing fluid from said container, a cleaning fluid reservoir, means for establishing a flow of fluid under pressure from said reservoir to the discharge passageway in said nozzle for flushing the interior of said container, means for simultaneously creating a suction flow from said nozzle to said reservoir for evacuating said container, valve means for controlling the flow of fluid to and from said nozzle, and actuating means for said valve means, said actuating means being adapted to delay operation of said suction controlling valve relative to said pressure valve until a level of cleaning fluid has been built up in said container at the beginning of a cleaning operation and to insure complete evacuation of residual fluid from said container at the end of a cleaning operation.

18. A self-contained apparatus for cleaning the interior of containers comprising in combination a cleaning nozzle adapted to be received in a container and having a discharge passageway therein with outlets for directing cleaning fluid on the interior surfaces of said container and an evacuation passageway for withdrawing fluid from said container, a cleaning fluid reservoir, means for establishing a flow of fluid under pressure from said reservoir to the discharge passageway in said nozzle for flushing the interior of said container, means for simultaneously creating a suction flow from said nozzle to said reservoir for evacuating said container, valve means for controlling the flow of fluid to and from said nozzle, and actuating means for said valves, said actuating means maintaining both valves open for simultaneous discharge and evacuation of cleaning fluid to flush the interior of said container and withdraw cleaning fluid therefrom while the same is in turbulent condition and foreign materials are suspended therein and maintaining said suction valve partially open upon termination of the cleaning operation to prevent backflow of cleaning fluid from said nozzle.

19. A self-contained apparatus for cleaning the interior of containers comprising in combination a cleaning nozzle adapted to be received in a container and having a discharge passageway therein with outlets for directing cleaning fluid on the interior surfaces of said container and an evacuation passageway for withdrawing fluid from said container, a cleaning fluid reservoir, means for establishing a flow of fluid under pressure from said reservoir to said nozzle for flushing the interior of said container, means for simultaneously creating a suction flow from said nozzle to said reservoir, valve means for controlling the flow of fluid to and from said nozzle, actuating means for said valves, said actuating means delaying operation of said suction controlling valve relative to said pressure valve in each cleaning cycle to provide an initial period of discharge

21

of fluid only followed by a period of simultaneous discharge and evacuation, said actuating means being designed to repeat said cleaning cycle a plurality of times during each complete cleaning operation.

20. A cleaning apparatus, as set forth in claim 19, wherein the actuating means is designed to continue suction of reduced degree in said nozzle upon termination of the last cycle of a cleaning operation to prevent backflow of the residual cleaning fluid from said nozzle at the end of the cleaning operation.

21. A self-contained apparatus for cleaning the interior of containers comprising in combination a cleaning fluid reservoir having means for supporting a group of containers to be cleaned on its periphery, a series of cleaning nozzles each adapted to be received in a container and having discharge and evacuation passageways therein for simultaneous flushing and evacuation of the interior of a container, means for conveying cleaning fluid under pressure to said nozzles for discharge therefrom, means for creating a suction in said nozzles for evacuating said containers, and automatically operable means for controlling the pressure and suction flow in said nozzles to limit the number of nozzles opened to such flow at any one time, said means operating in a sequence which subject each container to repeated cycles of flushing and evacuation.

22. A self-contained apparatus for cleaning the interior of containers comprising in combination a cleaning nozzle adapted to be received in said container and having a discharge passageway on all of the interior surfaces of the container and an evacuation passageway for withdrawing cleaning fluid from said container, a cleaning fluid reservoir, a pressure chamber, means for forcing cleaning fluid under pressure from said reservoir to said pressure chamber, means for reducing the pressure to sub-atmospheric in a portion of said reservoir, means connecting the discharge passageway of said nozzle to said pressure chamber, means connecting the evacuation passageway of said nozzle to said reservoir, valve means in said connecting means for controlling the flow of fluid therethrough, and actuating means for sequentially operating said valves to provide an initial period of discharge only followed by a period of simultaneous discharge and evacuation and a period of evacuation only at the termination of a cycle in the cleaning operation.

23. A cleaning apparatus as set forth in claim 22 wherein the means for controlling the operation of said actuating means is designed and adapted to actuate said valve through a plurality of cleaning cycles during each cleaning operation.

24. A self-contained apparatus for cleaning the interior of containers comprising in combination a cleaning nozzle adapted to be received in said container and having a discharge passageway on all the interior surfaces of the container and an evacuation passageway for withdrawing cleaning fluid from said container, a cleaning fluid reservoir, a pressure chamber, means for forcing cleaning fluid under pressure from said reservoir to said pressure chamber, a filter chamber in communication with said reservoir, means connecting the discharge passageway of said nozzle to said pressure chamber, means connecting the evacuation passageway of said nozzle to said filter chamber, means for reducing the pressure to

22

sub-atmospheric in a portion of said reservoir to create a suction in said reservoir and filter chamber for causing a flow of fluid through said evacuation connecting means and said filter chamber into said reservoir, valve means in said connecting means for controlling the flow of fluid therethrough, actuating means for operating said valves sequentially to provide an initial period of discharge only at the beginning of a cleaning cycle followed by a period of simultaneous discharge and evacuation and a period of evacuation only at the end of a cleaning cycle, and means for controlling the operation of said actuating means to actuate said valve through a plurality of cleaning cycles during a single cleaning operation.

25. A self-contained apparatus for cleaning the interior of containers comprising in combination a rotatable cleaning fluid reservoir, means for supporting a plurality of containers on said reservoir, a series of nozzles on said reservoir each adapted to be received in one of said containers and having a discharge passageway with outlets therein for directing cleaning fluid on all of the interior surfaces of said container and an evacuation passageway for withdrawing cleaning fluid from said container, means for establishing a flow of cleaning fluid under pressure from said reservoir to said discharge nozzles, means for simultaneously creating a suction flow from said nozzles to said reservoir, valve means for controlling the flow of fluid to and from said nozzles, actuating means for opening and closing said valves, said means being secured on said reservoir and rotating therewith, and a pair of stationary cams engaging respectively with the actuating means for operating the valves in said pressure lines and the actuating means for operating the valves in said suction lines said latter cam being conformed to delay opening of said suction valves with respect to said pressure valves and to continue the suction at a reduced value at the end of a cleaning operation.

26. A self-contained apparatus for cleaning the interior of containers comprising in combination a rotatable cleaning fluid reservoir, means for supporting a plurality of containers on said reservoir, a series of nozzles on said reservoir each adapted to be received in one of said containers and having a discharge passageway with outlets therein for directing a cleaning fluid on all of the interior surfaces of said container and an evacuation passageway for withdrawing cleaning fluid from said container, means for establishing a flow of cleaning fluid under pressure from said reservoir to said discharge nozzles, means for simultaneously creating a suction flow from said nozzles to said reservoir, valve means for controlling the flow of fluid to and from said nozzles, stationary cam means, and actuating means engaging with said cam means for opening and closing said valves, said cam means operating said actuating means to open said valves for simultaneously flushing and evacuating said containers and continuing evacuation at the end of the cleaning operation to completely drain said containers, said cams being conformed to operate only a limited number of actuating means at any one time.

27. A self-contained apparatus for cleaning the interior of containers comprising in combination a rotatable cleaning fluid reservoir, a plurality of cleaning nozzles secured on said reservoir and rotatable therewith, means for securing a plurality of containers on said reservoir with said cleaning nozzles projecting into said containers,

means for supplying cleaning fluid under pressure to said nozzles for flushing the interior of said containers, means for applying suction to said nozzles for evacuating said containers, valve means for controlling the flow of cleaning fluid in said supply and evacuation means, means for automatically operating said valve means in timed order when said reservoir is rotated to produce simultaneous flushing and evacuation of said containers for cleaning the same, driving means for said cleaning apparatus, a stationary post for supporting said reservoir, a clutch element fixed on said post and an idling clutch element co-axially arranged with respect to said post and operatively connected to said driving means, means for engaging said fixed and idling elements for locking said idling element in fixed position and thereby causing said driving means to be rotated about said post when said driving means is operating, and means connecting said driving means and said reservoir to cause the latter to be rotated when said driving means is rotating.

28. A self-contained apparatus for cleaning the interior of containers comprising in combination a rotatable cleaning fluid reservoir, a plurality of cleaning nozzles secured on said reservoir and rotatable therewith, means for supporting a plurality of containers on said reservoir with said cleaning nozzles projecting into said containers, a platform secured on said reservoir in fixed relation therewith, a pressure pump secured on said platform for establishing a flow of cleaning fluid under pressure from said reservoir to said nozzles, a vacuum pump secured on said platform for reducing the pressure in said reservoir to create a suction flow of cleaning fluid from said nozzles to said reservoir, means secured on said platform for driving said pumps and rotating said reservoir, valve means for controlling the flow of cleaning fluid in said pressure and suction means, means for automatically operating said valve means in timed order when said reservoir is rotated, a stationary vertical post extending axially of said reservoir for supporting the same, a clutch element fixed on said post, an idling clutch element co-axial with said post and operatively connected to said driving means, means for engaging said idler and said fixed clutch element for locking said idler in fixed position and thereby causing said platform and said reservoir to be rotated upon said vertical post by said driving means when said clutch elements are engaged.

29. A self-contained apparatus for cleaning the interior of containers comprising in combination a rotatable cleaning fluid reservoir, a plurality of cleaning nozzles secured on said reservoir and rotatable therewith, means for supporting a plurality of containers on said reservoir with said cleaning nozzles projecting into said containers, a platform secured on said reservoir in fixed relation therewith, a pressure pump secured on said platform for establishing a flow of cleaning fluid under pressure to said nozzles, a vacuum pump secured on said platform for creating a suction flow of cleaning fluid from said nozzles to said reservoir, driving means secured on said platform, valve means for controlling the flow of cleaning fluid in said pressure and suction means, means for automatically operating said valve means in predetermined order when said reservoir is rotated, a stationary vertical post extending axially of said reservoir for supporting the same, a thrust bearing on said post for rotatably supporting said reservoir thereon, a clutch element co-axially fixed on said post, an idling clutch element oper-

atively connected to said driving means, means for engaging said idling element and said stationary element for locking said idling element in fixed position and thereby causing said platform and said reservoir to be rotated upon said vertical post when said clutch elements are engaged.

30. In a self-contained apparatus for cleaning drums or other containers the combination comprising a rotatable cleaning fluid reservoir having a plurality of container supports thereon for supporting containers in cleaning position and a plurality of cleaning nozzles adapted to project into said containers, a pressure chamber, a pressure pump for conveying cleaning fluid under pressure to said pressure chamber, means connecting said pressure chamber and said nozzles for conveying cleaning fluid to said nozzles, a vacuum pump for reducing the pressure to sub-atmospheric in that portion of said reservoir above the level of the fluid therein, said vacuum pump having a capacity reduced with respect to said pressure pump sufficiently to permit said pressure pump and said vacuum pump operating in a normal manner to evacuate simultaneously cleaning fluid and air respectively from said reservoir without undue strain on either, means connecting said nozzles and the region of reduced pressure in said reservoir, control means for controlling the flow of cleaning fluid in said suction and pressure lines leading to and from said nozzles, means for rotating said reservoir, stationary cams engaging with said control means for operating the latter to open and close said valves when said reservoir is rotated, said cams being adapted to delay operation of said suction control means with respect to said pressure control means at both the opening and closing of the cleaning cycle.

31. In a self-contained apparatus for cleaning drums or other containers the combination comprising a rotatable cleaning fluid reservoir having a plurality of container supports thereon for supporting containers in cleaning position and a plurality of cleaning nozzles adapted to project into said containers, pressure and suction creating means in communication with said nozzles and said reservoir for effecting a forced flow of cleaning fluid to and from said cleaning nozzles, means operated upon rotation of said reservoir for automatically controlling the flow of fluid to and from said nozzles, means for driving said pressure and suction creating means and engageable with said reservoir for rotating the latter, an auxiliary nozzle adapted to be received in containers of such size or shape as to prevent their support on said reservoir for automatic cleaning, auxiliary nozzle connections communicating with said pressure and suction creating means, and manually controlled means on said connection for controlling the flow of cleaning fluid to and from said auxiliary nozzles for non-automatically cleaning said containers when said driving means is disengaged from said reservoir by simultaneous flushing and evacuation of the same.

32. A self-contained apparatus for cleaning the interiors of containers comprising in combination, a rotatable cleaning fluid reservoir, means for supporting a plurality of containers thereon in cleaning position, a plurality of cleaning nozzles adapted to be received in said containers for flushing said containers with cleaning fluid and evacuating the same therefrom, means for establishing a flow of cleaning fluid under pressure to said nozzles, means for applying suction to said nozzles for evacuating cleaning fluid from said containers to said reservoir, motor means for

operating said suction and pressure means and for rotating said reservoir, valve means for controlling the flow of cleaning fluid to and from said nozzles, stationary cams, valve operating means engaging with said cams for opening and closing said valves to control the flow of fluid to and from said containers, said cams being conformed to operate said valves sequentially and repeatedly for flushing said containers a plurality of times during each revolution of said reservoir, and being provided with an extended dwell along one portion thereof to permit removal of cleaned containers from said reservoir and loading of contaminated containers thereon.

33. The method of cleaning the interior surfaces of containers which comprises positioning said containers to establish a low point therein accessible from the opening in said containers, initially delivering a cleaning fluid under pressure to the interior of said containers and directing the same against all of the interior surfaces thereof until said containers have been partially filled with cleaning fluid, then continuing the discharge of fluid into said containers to continue the cleaning action and maintain the entrapped liquid turbulent and simultaneously applying a suction to the lowermost part of said containers for evacuating the cleaning fluid and the foreign material dislodged from said containers and suspended therein.

34. The method of cleaning the interior surfaces of containers which comprises positioning said containers to establish a low point therein accessible from the opening in said containers, initially delivering a cleaning fluid under pressure to the interior of said containers and directing the same against all of the interior surfaces thereof until said containers have been partially filled with cleaning fluid, then continuing the discharge of fluid into said containers to continue the cleaning action and maintain the entrapped liquid turbulent and simultaneously applying a suction to the lowermost part of said containers for evacuating the cleaning fluid and the foreign material dislodged from said containers and suspended therein, continuing said circulation of fluid until said containers have been cleaned, then discontinuing the discharge of fluid into the said containers and continuing the suction until the residual cleaning fluid has been withdrawn.

35. The method of cleaning the interior surfaces of containers which comprises positioning said containers to establish a low point therein accessible from the opening in said containers, initially delivering a cleaning fluid under pressure to the interior of said containers and directing the same against all of the interior surfaces thereof until said containers have been partially filled with cleaning fluid, continuing the discharge of fluid into said containers and simultaneously applying a suction to the lowermost part of said containers for evacuating cleaning fluid and the foreign material dislodged from said containers and suspended therein, then filtering said evacuated cleaning fluid to remove the foreign material therefrom.

36. The method of cleaning the interior surfaces of containers which comprises positioning said containers to establish a low point therein accessible from the opening in said containers, initially delivering a cleaning fluid under pressure to the interior of said containers and directing the same against all of the interior surfaces thereof until said containers have been partially filled with cleaning fluid, continuing the dis-

charge of fluid into said containers and simultaneously applying a suction to the lowermost part of said containers for evacuating cleaning fluid and the foreign material dislodged from said containers and suspended therein, filtering said evacuated cleaning fluid to remove the foreign material therefrom, recirculating said filtered cleaning fluid through said containers until the latter have been cleaned, then discontinuing the discharge of said fluid into said containers and continuing the suction until the residual cleaning fluid has been withdrawn.

37. The method of cleaning the interior surfaces of containers which comprises positioning said containers to establish a low point therein accessible from the opening in said containers, initially delivering a cleaning fluid under pressure to the interior of said containers and directing the same against all of the interior surfaces thereof until said containers have been partially filled with cleaning fluid, continuing the discharge of fluid into said containers and simultaneously applying a suction to the lowermost part of said containers for evacuating cleaning fluid and the foreign material dislodged from said containers and suspended therein, filtering said evacuated cleaning fluid to remove the foreign material therefrom, transferring said filtered cleaning fluid to a cleaning fluid reservoir, recirculating filtered cleaning fluid from said reservoir through said containers until the latter have been cleaned, then discontinuing the discharge of fluid into said containers and continuing the suction until the residual cleaning fluid has been withdrawn.

38. The method of cleaning the interior surfaces of containers which comprises positioning said containers to establish a low point therein accessible from the opening in said containers, initially delivering a cleaning fluid under pressure to the interior of said containers and directing the same against all of the interior surfaces thereof until said containers have been partially filled with cleaning fluid, continuing the discharge of fluid into said containers and simultaneously applying a suction to the lowermost part of said containers sufficient to evacuate turbulent cleaning fluid at the same rate that it is being discharged into the containers to maintain a level of turbulent fluid in said containers until the containers have been cleaned, then discontinuing the discharge of fluid into said containers and continuing the suction until the residual cleaning fluid in said container has been withdrawn.

39. The method of cleaning the interior surfaces of containers which comprises positioning said containers upon a carrier to establish a low point therein accessible from the opening in said containers, initially delivering a cleaning fluid under pressure to the interior of said containers and directing the same against all of the interior surfaces of said containers until said containers have been partially filled with cleaning fluid, continuing the discharge of fluid into said containers and simultaneously applying a suction to the lowermost part of said containers for evacuating cleaning fluid therefrom and such foreign materials as have been dislodged from said containers and are suspended in said cleaning fluid, then discontinuing the circulation of fluid to and from said containers and moving the same to advanced cleaning positions, repeating said flushing and evacuation in said containers at said advanced position until all of the foreign materials have been removed from said containers, terminating said cleaning operation by subjecting said con-

tainers to suction only for removing residual cleaning fluid.

40. The method of cleaning the interior surfaces of contaminated containers which comprises positioning said containers to establish a low point therein accessible from the opening in said containers, defining a path for said containers including an initial zone, a plurality of cleaning zones and a final zone, delivering a cleaning fluid under pressure to the interior of said containers in each of said cleaning zones and directing the same against all of the interior surfaces thereof, simultaneously applying suction to the lowermost point of said containers in each of said cleaning zones when the liquid level therein exceeds a predetermined amount and continuing said suction in the final zone, moving said group of containers

to transport each of said containers through each of said zones in succession and removing said containers reaching said final zone from said group and adding contaminated containers to said group at the initial zone to maintain a constant number of containers in said group.
